APPARATUS FOR DETERMINING THE
DEVIATION OF WELL HOLES AND CAS-
INGSJerome D. Lauder milk, Claremont, Calif., as-
signor of one-half to Mrs. S. Golson Harrell,
Los Angeles, Calif.

Application October 28, 1929. Serial No. 402,914

4 Claims. (Cl. 234—5.3)

This invention relates to an apparatus designed to determine the deviation of well holes and well casings from the perpendicular.

In drilling of well holes the well is intended to be drilled vertically downward. As a well is ordinarily drilled the depth of the well is measured solely by the length of the well or well casing. If the well deviates from the perpendicular, the depth of the well obtained by this measurement may be quite far from its actual depth. The drilling bit and drilling action may drill a spiral-like hole or may be drilled entirely off at an angle to the perpendicular. Heretofore there has been no inexpensive rapid means of measuring the deviation of a well hole from the perpendicular. It is the general object of the present invention to provide an apparatus which in a single descent of a well hole can be caused to survey the entire well hole and determine not only the slant or angle of deviation from the perpendicular of the well hole but which is also capable of determining the direction of deviation of each part of the well hole.

More particularly, an object of the present invention is to provide an apparatus having associated therewith compass and pendulum members with electrical indicating means by which, through simultaneous readings of the compass and pendulum members, the angle of deviation and direction of deviation of each part of the well hole may be accurately determined by passing the apparatus once down a well hole.

Various further objects and advantages of the present invention will be apparent from the description of a preferred form or example of an apparatus embodying the invention. For this purpose there is hereafter described, with reference to the accompanying drawings, one form or example of an apparatus which embodies this invention.

In the drawings:

Figure 1 is an elevation mainly in vertical section of the upper portion of the apparatus in position within a well casing.

Figure 2 is an elevation mainly in vertical section of the lower portion of the apparatus in position within a well casing.

Figure 3 is an elevation at right angles to Figure 1 of a part of the apparatus.

Figure 4 is a section through the line 4—4 of Figure 1.

Figure 5 is a plan view of the shutter.

Figure 6 is a diagram of the electrical connection of the pendulum.

Figure 7 is a plan view of the shutter and needle of the compass.

Figure 8 is an electrical diagram of wiring of the compass.

Figure 9 is a diagrammatic view of the receiver and connection with the testing apparatus.

Referring to the drawings, 1, indicates a well casing situated within a well hole which is intended to be surveyed by the apparatus. The apparatus includes a pendulum 2 and a compass member 3.

4 indicates a casing which is fluid-tight which houses the major operating parts of the apparatus. Said casing at its lower end is closed by a plate 5 to which is bolted a guide carrier member 6 carrying guiding rollers 7 rotatably mounted on the ends of arms 8. The opposite ends of the arms 8 are pivoted as indicated at 9, to the guide member 6. Guiding member 6 has a central stem 10 bearing spring members 11 engaging the center of the arms 8 for yieldingly urging the arms to pivot outwardly and bring their rollers 7 in engagement with the well casing. There is also provided ears 12 on the guide member which carry set screws 13 in position to engage the roller carrying arms 8 and limit their outward pivoting motion.

The upper end of the casing 4 is closed by a plate 14 which has upwardly extending cylindrical walls which in turn are closed by the flange plate 15 of an upper guide carrying member 16. The upper guide carrying member 16 is similar to the lower member, having the rollers 17, arms 18, spring 19 and limiting set screws 20. By the construction thus described, there is provided anti-friction rollers urged outwardly from each end of the testing device which function to retain the body of the testing device from frictional contact with the well hole or well casing.

The upper guide carrier 16 is hollow and receives a supporting and operating cable 21 of the apparatus, which cable passes through the chamber provided by the member 14 and is there engaged by a packing forming member 22 which comprises a casing 23 having an anti-friction roller bearing 24 engaging the bottom plate of the member 14 and which is provided at its upper end with a packing gland 25 and contains packing as indicated at 26, with the wiping arms 27 held in position by bolts 28. The wiper 27 extends through the plate of the member 14 and enters into a top member 29 of a rotor casing 30. The top member 29 has a ball bearing 31 engaging the plate of the member 14. The lower

end of the rotor 30 is provided with a bearing point 32 engaging in its center bearing recesses in the plate 5. By this construction, the rotor casing 30 is free to revolve within the outer ma- 5 jor casing 4.

The rotor 30 is constructed to have a heavy side, preferably by provision of a lead strip 33 which may have half of the cylinders of the rotor if desired. By the provision of a rotor hav- 10 ing a heavy side, one side of the rotor is in operation always definitely disposed at the lower side of the apparatus whenever there is any deviation of the well casing from the perpendicular such as will permit the apparatus assuming a position at an angle to the perpendicular, thereby 15 developing a position lower side.

The rotor 30 is provided with a central bar 34 pivotally mounting with pendulum 2. The pen- 20 dum 2 is provided with a number of selenium cells 35 mounted on a disc rigid with the bar 34 and connected with plus and minus mains 36 and 37, forming part of the supporting and operating cable 21, as indicated in Figure 6 of the drawings, i. e. between each of the selenium 25 cells there is a section of resistance wire 38 so that the total amount of resistance between the plus and minus mains 36 and 37 is dependent upon which, if any, of the selenium cells 35 is receiving light. The swinging part of the pen- 30 dum 30 comprises a shutter plate 39 having a narrow slit 40 in its upper center, which shutter disc 39 is weighted, as indicated at 41, so that the slit 40 is always in a definite position relative to the vertical. A casing 42 is pro- 35 vided on the opposite side of the shutter 39 from the selenium cells 35 and includes an incandescent bulb 43 connected with lines forming part of the operating supporting cable. By 40 this construction it will be seen that in opera- 45 tion, whenever the apparatus deviates from the perpendicular, the shutter of the pendulum member 40 will move over the series of selenium cells 35, the extent of motion depending upon the angle of deviation with the result that by 50 energizing one of the selenium cells, the resistance connecting mains 36 and 37 varies in proportion to said deviation.

The compass 3 is mounted in the lower end 55 of the rotor 30 and includes a compass case 44 which provides a gimbal support for a compass face 45 which is held always horizontal in the apparatus on account of the gimbal mounting. The compass face 45 has an axle 46 rotatably 60 mounting a compass needle member 47 which is in the form of an opaque disc provided with an opening 48. The compass face 45 is provided with circumferentially spaced apart selenium cells 50 connected by resistance turns 51 and wired with plus and minus mains 52 and 53, as indicated in Figure 8. Thus, the amount of 65 resistance between lead 52 and 53 in operation varies, depending upon which, if any, of the selenium cells is energized by light. The upper part of the compass casing 44 houses an incandescent bulb 55 shining upon the shutter 47 so as to illuminate the particular selenium cell 50 uncovered by the slot 48 in the compass.

In order to prevent the pendulum member 2 from vibrating in descent and to act as a damper for the same, I have provided a brake mem- 70 ber 60 pivoted to the rotor casing as at 61 and provided with a weight 62 which will normally hold the member stationary during descent. The brake member 60 is pivoted to the rotor 75 casing 30 so that it is applied to the pendulum

2 up until the apparatus passes a portion of the well hole and casing at a deviation from the perpendicular.

At such time the rotor casing 30, due to its heavy side, pivots to bring the pivot point of the 80 brake 61 at a lower position and the weight 62 then releases its pressure against the pen- dum 2, thereby permitting the pendulum to commence to operate.

In operation it will be apparent that any de- 85 sired means may be utilized for measuring during the descent of the apparatus the resistance between mains 36 and 37 controlled by the pen- dum 2 and the resistance between mains 52 and 53 controlled by the compass 3. The meas- 90 urement of these resistances, of course, should proceed simultaneously with the recording of the length of the supporting and operating cable 21 which has been placed out in lower- 95 ing the apparatus. In Figure 9 there is indicated one apparatus in diagrammatic form by which the operation of the pendulum and compass may be recorded automatically with the opera- 100 tion of the testing apparatus. The figure also discloses a full wiring diagram of the appa- 105 ratus. In the figure, 66 indicates a source of electricity connected by a line 67 to the incan- descent bulbs 43 and 55 of the pendulum and compass, respectively, and hence by the line 68 with the source 66. The source 66 also connects 110 with the positive lead 36 connected to the selen- 115 ium cells 35 of the pendulum and which are in turn connected with the return lead 37. The return lead 37 connects with the coils 69 with the magnet of the galvanometer 70, the rotor 71 of which is provided with a semispherical mirror 72 reflecting light from an incandescent bulb 73.

The positive main 52 connects with the selen- 120 ium cells 50 of the compass which in turn con- 125 nect with the negative line 53 which leads to the coils 74 of the magnet 75 of the galvanometer. The galvanometer is provided with a rotor 76 having a semispherical reflecting mirror 77 re- 130 flecting light from an incandescent bulb 78. 120 79 and 80 indicate lines connecting the bulbs 73 and 77 with the source of electricity 66. Above the galvanometers 70 and 75 there is mounted a moving photographic recording paper 135 81 which receives light from the semispherical 125 mirrors 72 and 77 of the galvanometers. By moving this photographic recording paper, at a rate proportional to the descent of the test- 140 ing apparatus, there will be automatically re- 130 corded the deviation of the well hole from the vertical, the direction of deviation of the proper coordination relative to the depth of the testing apparatus.

While the particular form of apparatus herein described is well adapted for carrying out the objects of the invention, it is to be understood that various modifications and changes may be made in the details of construction and various substitutions of equivalents made and that all such changes, modifications and substitution of equivalents come within the scope of the invention as defined by the appended claims.

I claim:

1. An apparatus for testing deviation of a well hole which comprises, a body member, an instrument carriage mounted by said body member to freely swivel about the axis of the body, a pen- dum carried by said instrument carriage and adapted to swing in accordance with the angle 145 of deviation from the perpendicular, means for 150

- transmitting to the surface of the well the position of said pendulum, said means including a plurality of resistances and a means in the pendulum for cutting out part of the resistance in accordance with the position of said pendulum. 5
2. An apparatus for recording the deviation of a well hole or casing which comprises, a body, a carrier swivelled to said body and weighted so as to possess a normally lower side, a pendulum carried thereby, and means for transmitting to the surface of the well the position of said pendulum, said means including resistances connecting selenium cells, a shutter connected with said pendulum, and a source of light. 10
3. An apparatus for recording the deviation from the perpendicular of a well hole or casing which comprises, a body, an instrument carrier rotatably mounted by the body and provided with a weighted side, an instrument carried by 15 said carrier, a plurality of selenium cells con-
- necting resistances, and means on said instrument for successively admitting light to said selenium cells in accordance with the motion of said instrument. 80
4. An apparatus for recording the deviation from the perpendicular of a well hole or casing which comprises, a body, a cable for supporting said body while it is moving into and out of the well hole, said cable including a plurality of electrical conduits, an instrument carrier mounted by the body to revolve axially, said instrument carrier being weighted to maintain one side lowermost when the body deviates from the perpendicular, and a gimbal mounted compass carried by said body, electrical resistances associated with said compass, and means for cutting out said resistances in accordance with the positions of said compass, said electrical conduits being connected to said resistances. 85 90
